United States Patent Office.

H. A. ENGELS, C. H. ENGELS, AND JOHN WIELAND, OF SAN FRANCISCO, CALIFORNIA.

Letters Patent No. 63,374, dated April 2, 1867.

MALT-DRYING APPARATUS.

The Schedule referred to in these Letters Patent and making part of the same.

Be it known, to whom it may concern, that we, H. A. ENGELS, CHARLES H. ENGELS, and JOHN WIELAND, of San Francisco, county of San Francisco, and State of California, have invented a new and improved Malt-Drying Apparatus; and we do hereby declare that the following is a full and exact description thereof, reference being had to the accompanying drawings, and to the letters of reference marked thereon, and of which—

Figure I represents a view of the apparatus, showing the long side of it, and by leaving out those doors which the operative must open to get access to the two compartments of each kiln; also a view of the interior arrangement; also a view of the end of the apparatus where the top funnel *a*, with worm *p*, and picking-shaft *q*, is constructed.

Figure II is a front elevation of the last-mentioned end of the apparatus, showing, by means of dotted lines, the positions of the important interior parts, like the steam pipes *k k*, the several shafts *r r*, the worm *p*, the picking-shaft *q*; also, externally, the funnel *a*, part of the flue *m*, the connecting funnel *d*, the supply pipes for the current of hot air *l l*, the several cam-wheels *s s' s''*, attached to the middle shafts *r r' r''*, and the driving-wheel *t*.

Figure III is a "horizontal section" of the apparatus, showing the entire perforated bottom of the kiln, under which run the steam pipes *k k*, as indicated by dotted lines; all rakes of one set are seen, each attached to two beams, which are lifted with the whole set of rakes, and moved forward and backward by the two cranks of each of the three shafts *r r*.

Figure IV represents a means of passing continually the grains through the apparatus, and over the chute *e f* into the box *g*, and by an elevator, *h*, up again into first funnel *a*, till the malt is done.

The nature of my invention is as follows:

The apparatus causes a saving of time, space, labor, and fuel, and is a self-feeding and turning kiln, or rather a number of connected kilns, one immediately above the other, each only about twenty-five inches high, and each worked by steam power, heated by steam, and heated and ventilated by an artificial current of hot air. This apparatus will do away with the unhealthy manual labor of turning of the grains in the large kilns, generally occupying two stories of a building, and will furnish, in about one-sixth of the time usually taken by the old process, a much sweeter and better malt of uniform quality. It will prevent a part of the grains from becoming what is termed "glassy," which will amount to a gain of from ten to twenty per cent. of soluble sugar, or of better yielding malt, as a result of the rapid removal of all dampness from the sprouted grains to be dried on their several kilns in the apparatus. The inventors beg to direct attention to their new mode of stirring or turning the grains, spread as above mentioned, all at the same time, in the several kilns, and by the same set of rakes, without propelling the grains any further than the extreme reach of one rake, say about ten to twelve inches, (the diameter of the revolution of each crank,) that is to say, by changing at the will of the maltster the first-described full revolution of the cranks on the shafts *r r*, which move the different sets of rakes into an oscillating movement by which the grains will be only raked forward and backward, and at the same time stirred around and mixed. Of considerable moment, and forming a prominent part of what the applicants believe to be their invention, is the introduction of the hot-air current over and under the spread grains in their apparatus, and also the application in their malt-kilns of the usual steam pipes under the perforated plate bottoms, combined with the current of hot air forced over and under the grains spread out and turned by their sets of rakes on the perforated bottoms. They finally may point to the facility of constructing of from six to eight of their kilns one above the other, each only twenty-five inches or more in height between the floor and ceiling of the same story in any building of the usual dimensions.

To enable others skilled in the art to make and use our invention, we shall proceed to describe its construction and operation.

The elevator *h* drops the sprouted grains into the funnel *a* on the top of the apparatus, where they are passed by the revolving-worm *p* to the picking-shaft *q*, revolving below said worm. This shaft does the separating of clumps of grains matted and grown together. The grains now enter the apparatus and its uppermost kiln. Each kiln consists of two compartments, viz, the upper one, for the grains spread on the usual perforated at the bottom, where they are turned and propelled by a set of rakes, *b*, these rakes being moved by three shafts;

r r, and their cranks, while the lower compartment *i i*, beneath the perforated bottom, serves for receiving the parched sprouts falling through the slits above, and also for introducing the steam-conducting pipes *k k*, both compartments being besides heated and ventilated by a current of air, this air being brought on by the distributing pipe *l*, and carried, in passing the apparatus, through the pipes *n n* and *o o*, into a flue, *m*, at the end of said apparatus. Said current of hot air also serves for carrying off, by its force, the dampness, carbonic acid, sulphurous gases, husks, &c., and assists in the heating and drying the grains of malt. The floor of each compartment *i i* forms, as is apparent, the roof and cover of the kiln next below. The sprouts are swept out and removed by the manual labor of the maltster, who has an access to each kiln by means of two trap-doors constructed on one of the long sides of the apparatus, as mentioned in Fig. I. The number of kilns, each measuring about twenty-five inches in height, may range from floor to top of the apparatus in numbers depending upon the size and capacity of the latter. Having entered the apparatus by means of the elevator, the worm and the picking-shaft, as stated above, the sprouted grains are caught under the first rake, and by the next revolution of the cranks propelled to within the reach of the second of the same set of rakes, and thus raked along step by step over the perforated plate *c* of the first or upper kiln, till all is covered and the grains drop by means of the funnel *d* upon the perforated plate bottom *c* of the second kiln, to be conducted in the same manner, but in an opposite direction, to the end of this kiln, whence they will pass through funnel *d'* down to the third kiln on its bottom *c''*, moving in the same direction with the first, &c., till all grains are spread over as many perforated kiln-bottoms as may be desirable to have constructed, in accordance to the capacity of the apparatus. The dry malt then passes out of the lowest kiln over a chute, *e f*, into a receiving-box, *g*, and, if needed, by the means of the elevator *h*, up again into the first funnel *a*, till the malt is done.

Having thus described the construction and operation of the apparatus, what we claim to be our invention, and desire to secure by Letters Patent, is—

1. The mode of malt drying in which the grains are mechanically carried into and spread about the kiln, then thereto turned and propelled by rakes, and at the same time submitted to a current of hot air combined with the heat of steam pipes, in a manner substantially as described above.

2. The combination and arrangement of elevator *h*, worm *p*, picking-shaft *q*, kilns *i*, rakes *b*, shafts *r r*, funnels *a a*, and *d d*, steam pipes *k k*, hot-air pipes *l n n o o*, flue *m*, and chute *e f*, in a manner and for the purpose described.

San Francisco, November 16, A. D. 1866.

H. A. ENGELS,
CHARLES II. ENGELS,
JOHN WIELAND.
